INVENTOR
Harold B. Richards
BY
Frederick W. Parker
ATTORNEY

UNITED STATES PATENT OFFICE.

HAROLD B. RICHARDS, OF RYE, NEW YORK.

SIPHON.

Application filed November 17, 1925. Serial No. 69,564.

This invention relates to apparatus for flushing purposes wherein a reservoir is to be discharged by means of a siphon, and my improvement is directed particularly to 5 novel means, under the control of an actuating device, for permitting the siphon to function.

Heretofore, so far as I am aware, flushing by siphonage has been entirely automatic, 10 causing the reservoir discharge to be intermittent with each refilling operation, and while desirable for use in public toilets and the like, this automatic intermittency of discharge is not required in dwellings or the 15 like, where control is necessary to provide the flushing discharge as occasion demands.

Therefore my invention consists broadly in adapting discharge by siphon to house or individual room usage, and to this end it 20 embodies the employment of an air trap that normally maintains a break in the siphon, together with relief means for said air trap, automatically operating through the agency of an auxiliary siphon, that it- 25 self functions under the control of simple, manually actuatable means.

Also my invention includes means whereby, after discharge of a reservoir, which 30 may have the effect of removing the water seals from the traps both in the discharge system of the reservoir and the closet bowl or the like, said traps will be automatically refilled.

Other features and advantages of my in- 35 vention will hereinafter appear.

The drawing shows in vertical section a tank or reservoir fitted with my improved apparatus for discharging its contents by siphonage, also showing the control means 40 therefor and means for automatically replenishing the tank.

In said drawing let 1 indicate a tank or reservoir such for example as is used in containing water used for flushing toilets and 45 the like, 2 a discharge outlet in the base of said tank, and 3 an inlet pipe for refilling purposes.

As refilling means I show herein a pend- 50 ent nozzle 4 forming the terminal of a valve structure 5, in connection with pipe 3 by a pipe 6, and under control of a float member 7, adapted to open the valve and permit ingress of water to the tank when the water level therein is lowered.

55 The particular valve mechanism thus gen-

erally referred to and illustrated needs no further comment herein, since it forms the subject matter of another application for patent filed by me concurrently herewith.

Besides, my improved siphonage discharge 60 system is not limited to use in conjunction with the said particular valve mechanism but may be employed in tanks fitted with other forms of inlet control.

Secured within the outlet 2 is a hollow 65 fitting 8 which, among other functions, serves as a support for a vertically disposed pipe 9, to which it is attached, said pipe being disposed within said fitting, in concentric, spaced relation to a delivery pipe 70 10, through which water is to be conveyed, for flushing purposes, as to a closet bowl, not shown.

The pipe 9 is part of a hollow coil that in- 75 cludes the bend 11, vertical portion 12, bend 13, vertical portion 14, bend 15 and vertical portion 16, the latter terminating in an open end 17 opposed to and suitably spaced from the tank base. As shown the vertical portions 12, 14 and 16 constitute 80 straight lengths arranged in parallelism.

The coil thus represented, all parts where- 85 of excepting the lower portion of pipe 9 are located below the normal water level in the tank, here indicated at 18, is intended to provide a siphon for discharging the tank contents down to the low level at the pipe end 17, leaving behind a water seal in the coil portions 12, 14 that provides an air pocket 90 in the bend 15 and prevents flow through the coil of water rising in portion 16 as the tank refills. Consequently, when the tank has been completely refilled up to its nor- 95 mal level, such for example as that indicated at 18, only the water of the water seal entrapped in coil portions 12, 13 and 14 will remain in the coil, with the exception of the water that rises in coil portion 16 to a point at which air entrapped in bend 15 is com- 100 pressed under the hydrostatic pressure ex- 105 ereted by the tank contents.

It therefore becomes necessary to relieve the air pressure in bend 15 in order to per- 105 mit a siphoning action to be established through the coil, and this object is accom- plished by me in the following manner.

Located within the tank, and, as here shown, supported by fitting 8, is a tubular casing 19, which is provided with closure means 20 at its lower end, and whose upper 110

open end 21 extends above the water level 18. An aperture 22 through the wall of the casing, near its lower end, permits water from the tank to rise equally within said casing. A tube of inverted U-shape is supported within casing 19, one leg 23 of said tube projecting through the closure 20 and opening into the hollow space 24 within fitting 8, while the other leg 25 is shorter, its open end being spaced from closure 20, and lying in about the horizontal plane of the mouth 17 of pipe 16, or preferably slightly above said plane.

The legs 23, 25 are connected at their upper ends by a bend 26 that extends above the water level 18, so that under inactive conditions, with the tank filled, leg 25 only contains a column of water, while leg 23 is empty. It is my purpose, however, to provide means for creating a siphon through this inverted U-tube, to thereby discharge casing 19, faster than it can refill, through aperture 22, for a reason which will presently appear. Therefore I provide means whereby the level of water in casing 19 may be quickly carried to a point above bend 26, by which means the column in leg 25 will carry over the bend 26 into leg 23, thus establishing the desired siphon to discharge casing 19, through fitting 8 and into delivery pipe 10. Since the casing 19 is connected by means of a pipe 27 with bend 15, it follows that the air trap that had been formed in said bend becomes relieved upon the discharge of casing 19, and thereby the major siphon of the coil is started for discharge of the tank through pipe 9 and into the delivery pipe 10.

As convenient means for raising the level of water in casing 19 I have shown a cup in the form of a sleeve 28 concentric with said casing and slideable thereon, the base 29 of said cup normally resting for support upon a shoulder 30 extended from said casing. Holes 31 through the wall of the cup permit ingress of water from the tank, so that said cup is normally filled. Now, it is apparent that if the cup be elevated to a point where a portion thereof exceeds the height of casing 19, the cup contents will thereby raise the level of water above bend 26, thus accomplishing the object already premised of starting the siphon through the inverted U-tube. Various means may be resorted to for elevating cup 28, and for example I have shown a yoke 32, pivotally connected to the cup sides and continuing into a telescopic lever arm 33, which is provided with a usual form of pivotal handle 34, for convenient manual operation.

It often happens when flushing a closet bowl that the trap containing a water seal intended to prevent the escape of sewer gases is left dry, and similarly the water seal in that part of my improved siphon

coil included in portions 12, 13 and 14 is exposed to the same contingency. Therefore I provide a pipe 35 which extends from the tank filling nozzle 4 to the top of bend 11, for the supply under service pressure, of a small column of water, whose flow will be divided, part thereof falling through pipe portion 9 and delivery pipe 10 into the trap below the bowl (neither bowl nor trap being here shown) and part entering through pipe portion 12 to fill it and pipe portion 14, thus recreating the water seal in the coil.

In the operation of my improved flushing system it will be appreciated that upon the emptying of casing 19 through the inverted U-tube, which has had the effect of relieving air pressure in bend 15 by means of tube 27, the siphon in said inverted U-tube thereby becomes broken, and then casing 19 can refill through aperture 22.

Variations within the spirit and scope of my invention are equally comprehended by the foregoing disclosure.

I claim:

1. A liquid discharge system including a tank and comprising a main siphon which includes a water sealed air pocket constituting a break in the siphon, relief means for said air pocket, auxiliary siphonage means for controlling said relief means, and manually actuatable means, operable only when the tank is approximately filled, for adding a quota of liquid to said auxiliary siphonage means, to establish a siphon therein.

2. A liquid discharge system including a tank provided with filling means and an outlet, a coil within said tank to discharge said tank by siphonage, said coil arranged to provide a water sealed air pocket constituting a break in the siphon, relief means for said air pocket, auxiliary siphonage means for controlling said relief means, thereby permitting the siphon to function, and manually actuatable means operable when the tank is approximately filled for adding a quota of liquid to said auxiliary siphonage means, to establish a siphon therein.

3. The combination with a liquid discharge system comprising a siphon which includes a water sealed air pocket constituting a break in the siphon, of a liquid containing casing having siphonage discharging means, means of communication between said casing and air pocket and manually actuatable means operable only when the tank is approximately filled, for adding a quota of liquid to said casing to establish a siphon therein, thereby reducing the pressure in said casing and causing the pressure in said air pocket to be relieved.

4. In a flushing system including a tank provided with controlled filling means and an outlet, and a coil therein to discharge said tank by siphonage, said coil arranged to provide a water sealed air pocket consti-

tuting a break in the siphon, the combination of a casing within said tank having relatively small means of communication with said tank, said casing projecting above the water level in the tank, siphonage means for discharging said casing, said siphonage means being inoperative at normal water level, means actuatable to quickly raise the wa-

ter level in said casing, thereby starting the siphon therein, and means of communication between said casing and air pocket, whereby pressure in the latter becomes relieved upon the discharge of said casing. ¹⁰

Executed this 14th day of November, 1925.

HAROLD B. RICHARDS.
